UNITED STATES PATENT OFFICE.

WILLIAM MAXWELL, OF FULHAM, COUNTY OF MIDDLESEX, ENGLAND.

ROTARY EXHAUST-PUMP.

SPECIFICATION forming part of Letters Patent No. 364,532, dated June 7, 1887.

Application filed October 8, 1886. Serial No. 215,709. (No model.) Patented in England December 15, 1885, No. 15,478; in France September 25, 1886, No. 178,731, and in Belgium September 29, 1886, No. 74,676.

To all whom it may concern:

Be it known that I, WILLIAM MAXWELL, a citizen of England, residing at Claybrook Road, Fulham, county of Middlesex, England, have 5 invented a new and useful Rotary Exhaust-Pump, (for which I have obtained a patent in Great Britain, dated December 15, 1885, No. 15,478; in France, dated September 25, 1886, No. 178,731, and in Belgium, dated September 10 29, 1886, No. 74,676,) of which the following is a specification.

My invention relates to a construction and arrangement of rotary exhaust-pump applicable for exhausting air from vessels—such as 15 the bulbs of incandescent lamps—as I will describe, referring to the accompanying drawings.

Figure 1 is a vertical section, and Fig. 1^a is a plan, of a rotary pump according to my invention, arranged to act, in lieu of a Sprengel pump, for producing a high degree of vacuum. Fig. 1^b is a vertical section showing a modification.

Referring first to Figs. 1 and 1^a, A is a basin 25 containing mercury, and having a central hollow boss, B, from which curved tubes C, of small bore, extend upward and outward to an annular trough-rim, D. From the center of the boss B a tube extends upward through a 30 bearing and within a stationary tube, F, which is connected to the lamp-bulbs or other vessels that have to be exhausted. A cup, G, is charged with mercury, which, rising in the annular space between E and F, constitutes a 35 hydraulic joint, the height of column being made sufficient to balance the difference between the external and the internal pressures. When the basin A and the apparatus within it are caused to revolve in the direction of 40 the arrow, mercury, with which the basin is charged, entering the tubular part of the spindle by apertures b and passing by narrow channels the plug b', finds its way in successive portions into the tubes C, and these 45 portions are propelled along these tubes by centrifugal force, each portion of mercury constituting a fluid piston which carries away in front of it a portion of air which has descended the tube E and entered the tubes C. The

mercury is discharged from the tubes C into 50 the trough-rim D, whence it overflows into the basin A, returning to the center to supply the tubes C afresh. The air carried by the mercury along the tubes C separates at the rim and escapes through apertures in the lid 55 of the basin.

By inclosing the whole apparatus in a chamber exhausted by an ordinary air-pump, so that the pressure acting against the outflow along the tubes C is considerably below that 60 of the atmosphere, the rotary pump may be rendered effective at moderate velocity for producing a high degree of vacuum.

Obviously, instead of mercury, a metal fusible at a moderate temperature may be employed, the apparatus being kept sufficiently hot to maintain its fused condition.

By providing the trough D, into which the tubes C deliver the mercury, a store of mercury is maintained at the mouths of the tubes, 70 which can flow back into the tubes on a decrease of speed occurring, and thus prevent the air from entering so as to destroy the vacuum formed.

According to the modified form of pump 75 shown in Fig. 1^b the lid O of the basin A is stationary and has suspended from it a stationary shelf, S, along which the mercury discharged from the tubes C returns to supply the hollow of the boss B through small holes. 80

Having thus described the nature of my invention and the best means I know of carrying the same out in practice, I claim—

1. A rotary pump for exhausting air, consisting of a revolving hollow boss or chamber 85 from which radiate curved tubes of small diameter, and which communicates by an axial tube with the space from which the air is to be exhausted, and by apertures with a vessel containing mercury revolving therewith, the 90 rotation of the boss with its tubes causing air, together with mercury, to be ejected from the chamber by centrifugal force through the tubes, while the ejected mercury flows by gravity back into the chamber again, substantially as described.

2. In a rotary pump for exhausting air, the combination of a revolving basin, A, contain-

ing mercury, the hollow boss B, with curved tubes C, extending thence to the trough-rim D, and the tubes E and F with cup G charged with mercury, substantially as and for the purpose herein set forth.

In testimony whereof I have signed my name to this specification, in the presence of two

subscribing witnesses, this 7th day of September, A. D. 1886.

WM. MAXWELL.
